UNITED STATES PATENT OFFICE.

WILLIAM E. LAWN AND JAMES A. RYAN, OF ROCHESTER, NEW YORK, ASSIGNEES TO
AUTOMATIC RAILROAD APPLIANCES CO. INC., OF ROCHESTER, NEW YORK, A COR-
PORATION OF NEW YORK.

AUTOMATIC TRAIN-STOP MECHANISM.

1,215,390.

Specification of Letters Patent. Patented Feb. 13, 1917.

Application filed March 14, 1914. Serial No. 824,594.

To all whom it may concern:

Be it known that we, WILLIAM E. LAWN and JAMES A. RYAN, both of Rochester, in the county of Monroe and State of New York, have invented certain new and useful Improvements in Automatic Train-Stop Mechanisms; and we do hereby declare the following to be a full, clear, and exact description of the same, reference being had 5 to the accompanying drawings, forming a part of this specification, and to the reference-numerals marked thereon.

Our invention relates to automatic train stop mechanisms, with particular reference 15 to mechanically controlled devices for stopping a train by the application of the brakes, when a predetermined condition exists, and it has for its object to provide a structure of simple form and arrangement, and that 20 can be relied upon for a certain operation at all times. A further purpose of the invention consists in affording a combination that requires a small number of parts arranged in such a manner as to enable the engineer 25 to maintain a complete and perfect control over the apparatus at all times. Still another object of our improvement resides in affording an arrangement whereby the train 30 may be brought to a standstill either through the regular or service system or through the emergency system, depending upon the particular conditions. A further object resides 35 in placing the apparatus under the control of the engineer, so that he may be enabled to pass a danger condition, if desirable, without effecting an automatic setting of the 40 brakes. To these and other ends the invention consists in certain improvements and combinations of parts all as will be herein- 45 after more fully described, the novel features being pointed out in the claims at the end of the specification.

In the drawings:

Figure 1 is a side elevation, showing the 45 rear part of a locomotive equipped with our invention;

Fig. 2 is a sectional view on the line 2^a—2^a of Fig. 1;

Fig. 3 is an enlarged side elevation of 50 the apparatus;

Fig. 4 is a sectional view on the line 4^a—4^a of Fig. 3;

Fig. 5 is an enlarged sectional view through the controlling valve and casing;

Fig. 6 is a plan view of the parts; 55

Fig. 7 is a view in end elevation, looking to the right of Fig. 3, and

Fig. 8 is a sectional view on the line 8^a—8^a of Fig. 3.

Similar reference numerals in the several figures indicate the same parts.

In carrying out our invention, we provide means connected with the air brake system so as to control a train either by a service application or by an emergency application of the brakes, as determined by a preliminary adjustment, and we connect the controlling devices both to the service pipe and to the emergency pipe so that they may be placed selectively under the control of the operating devices. In the present embodiment, A designates the equalizing reservoir which is connected by the pipe a' with the valve casing to be described hereinafter. When it is desired to stop the train by a service application of the brakes the pressure is reduced in the reservoir A, and a² 65 is a hand valve for cutting off the reservoir A from the controlling devices when it is desired to make only an emergency application. The latter operation is effected by reducing pressure in the emergency pipe B, which is connected with the valve casing before mentioned by the pipe b', the latter being provided with a hand valve b² for cutting it off from the automatic controlling devices. 70 80 85

The casing referred to is designated at C, and is of annular formation as shown, to support the valve D which is preferably in the form of a sleeve rotatably and slidably arranged on the casing. In Fig. 4, the valve is shown in closed position, while in Fig. 5 it is shown open to permit reduction of air pressure in the system. The valve comprises a removable head d' having openings d² 90 extending therethrough and an enlargement d³ adapted to coöperate with a seat formed on the end of the service pipe a', to maintain pressure in said pipe when the valve is closed. Under the last mentioned conditions, pressure is maintained in the emergency pipe by a seat d⁴ carried by the casing and adapted to coöperate with the valve head d'. The pipe a' is preferably 95 100

provided at its end, within the casing C with a sleeve a^3 , forming a chamber around the end of the pipe and communicating with the interior thereof by means of openings 5 a^4 , the purpose of this construction being to prevent freezing between the valve and the end of the pipe a' , which would otherwise tend to interfere with the proper operation of the mechanism when subjected to cold.

10 In order to move the valve B longitudinally on the casing C, we provide means for rotating the valve as will now be described, and also provide it with projections d^5 , which engage cam slots d^6 in the valve casing so as to impart the necessary longitudinal movement to the valve as it is rotated. The valve carries an arm d^6 which lies normally in the position shown in Fig. 3, and is adapted to be moved to the position shown in 15 dotted lines where it is held by a spring actuated latch d^7 pivoted at d^8 and controlled by the spring d^9 . The latch d^7 co-operates with the stop or projection d^{10} formed on the arm d^6 so that when the arm is raised by 20 the operating means, it will be held in such position and thus insure application of the brakes. E is a lever pivotally mounted on a bracket E² which is carried by the frame E³, the free end of the lever being arranged to engage and operate the arm d^6 . The lever E is movable between stops e' and e^2 , and is provided with a buffer e^3 co-operating with the upper stop. e^4 is an adjustable slide mounted upon the lever E and 25 adapted to contact with the actuator which we will now describe.

The actuator embodies a rod F which is slidably mounted in a sleeve F', and rotatively carried by the rod F is a downwardly 30 projecting bracket f provided at its end with an upwardly extending arm f', adapted to engage the base of the slide e'. The arm f' embodies a guideway to receive an adjustable bar f² carrying a foot f³ at its lowermost end which is adapted to engage a 35 specially constructed stationary or other abutment or roadside member. The bar f² is provided with a series of notches f⁴ by which it may be adjusted within the guideway, being held in place by an adjusting bolt f⁵ co-operating with said notches. The abutment for effecting the operation is of 40 gradual inclination so as to engage the foot f³ without causing too sudden jar of the parts, although it will be understood that the form and construction of the abutment which sets the controlling devices into operation is unimportant so far as concerns the 45 present invention, which has to do particularly with the structure of the controlling devices on the train.

The rod F is slidable within the sleeve F', the latter being slotted to receive the bracket f, the purpose of such longitudinal adjustment being to enable the foot f³ to be moved

away from operative relation with the abutment, in case the engineer should desire to pass the abutment without subjecting the brakes to automatic operation. To this end, the rod F may be provided with a piston H mounted thereon and movable within the cylinder H', which is connected with the air system by a pipe h, to which pressure can be admitted by the engineer when desirable. It will be seen that when the parts are in 75 normal position shown in Figs. 3 and 4, if pressure is admitted to the pipe h, the piston H will be moved along the cylinder H', carrying the actuator out of the path of the abutment, and after the latter is passed, the 80 actuator is returned to its normal position by the spring h', upon cutting off the supply of air pressure to the pipe h. The normal position of the actuator is determined by a stop f⁶ which is engaged by a lug or 85 extension f⁷ carried by the arm f'.

We claim as our invention:

1. In an automatic train stop mechanism, the combination with the service pipe and the emergency pipe of an air brake system, 90 of a valve controlling both of said pipes, and automatically operable means arranged on the train and having operative connection with the valve.

2. In an automatic train stop mechanism, the combination with the service pipe and the emergency pipe of an air brake system, 95 said pipes terminating in an annular casing, of a rotary valve movable on said casing and controlling both of said pipes, and automatically operable means arranged on the train and operatively connected with the valve.

3. In an automatic train stop mechanism, the combination with a valve controlling the 105 air brake system, of a pivoted lever co-operating with the valve, and an actuator in engagement with the lever and provided with a shoe adapted to engage a stationary abutment while the train is moving, the actuator being laterally adjustable to move the shoe 110 out of co-operative relation with the stationary abutment.

4. In an automatic train stop mechanism, the combination with a valve controlling the 115 air brake system, of an actuator operatively connected with the valve and provided with a shoe adapted to engage a stationary abutment while the train is moving, the actuator being laterally adjustable to move the shoe 120 out of co-operative relation with the stationary abutment.

5. In an automatic train stop mechanism, the combination with a valve controlling the 125 air brake system, of a pivoted lever co-operating with the valve, and an actuator in engagement with the lever and provided with a shoe adapted to engage a stationary abutment while the train is moving, the actuator being laterally adjustable to move the shoe 130

out of coöperative relation with the stationary abutment, and fluid pressure controlled means for adjusting the actuator.

6. In an automatic train stop mechanism, 5 the combination with a valve controlling the air brake system, of an actuator operatively connected with the valve and provided with a shoe adapted to engage a stationary abutment while the train is moving, the actuator 10 being laterally adjustable to move the shoe out of coöperative relation with the stationary abutment, and fluid pressure controlled means for adjusting the actuator.

7. In an automatic train stop mechanism, 15 the combination with a valve controlling the air brake system, of an actuator operatively connected with the valve and provided with a shoe adapted to engage a stationary abutment while the train is moving, the actuator 20 being rotatable to effect operation of the valve and slidably laterally to move the shoe out of operative relation with said abutment.

8. In an automatic train stop mechanism, the 25 combination with a valve controlling the air brake system, of an actuator operatively connected with the valve and provided with a shoe adapted to engage a stationary abutment while the train is moving, the actuator 30 being rotatable to effect operation of the valve and slidably laterally to move the shoe

out of operative relation with said abutment, and fluid pressure controlled means for adjusting the actuator.

9. In an automatic train stop mechanism, 35 the combination with a service and emergency pipes of an air brake system, of a single controlling means coöperating with both of said pipes, and means on the train actuated by an abutment along the track for 40 operating said controlling means.

10. In an automatic train stop mechanism, the combination with the service and emergency pipes of an air brake system, of controlling means coöperating with each of said 45 pipes, and instrumentalities on the train actuated by an abutment along the track for operating said controlling means.

11. In an automatic train stop mechanism, the combination with the service and 50 emergency pipes of an air brake system, said pipes terminating in a casing, of a valve movable on said casing and controlling both said pipes, and means on the train actuated by an abutment along the track for 55 operating said valve.
